UNITED STATES PATENT OFFICE

VICTOR C. NORQUIST, OF KANSAS CITY, MISSOURI

METAL-PLATE-FLANGING MACHINE

Application filed June 21, 1926. Serial No. 117,399.

This invention relates to metal plate flanging machines and more especially to machines for flanging circular plates to be used as tank bottoms and the like, and my object is to produce a flanging machine adjustable for flanging plates of different thickness and diameter and adapted for turning the flanges to stand at different angles with respect to the plane of the body of the plates without appreciably distorting such body or the flanges as to gage or thickness and hence without weakening the metal at the bending points. A further object is to produce a machine of this character in which the plate is preferably revolved on the application of automatic power, and by which the bearing of the flanges will be accomplished through the application of manual or other power.

With these general objects in view the invention consists in certain novel and useful features of construction and combinations of parts as hereinafter described and claimed; and in order that it may be fully understood, reference is to be had to the accompanying drawings, in which:—

Figure 1 is a side view of a machine embodying the invention.

Figure 2 is a plan view of the same.

Figure 3 is a section on the line III—III of Figure 2.

Referring to the drawings in detail, 1 indicates a trackway or pair of parallel rails suitably anchored, and mounted upon said rails and centrally thereof is a post 2 forming a journal and support for a hand-operated bolt 3 extending longitudinally of the rails and engaging the lower arm of a yoke 4 for the purpose of imparting endwise movement to the yoke longitudinally of the trackway. The said yoke is supported upon an angle plate support 5 fitting upon the rails 1 for slidable movement thereon. The lower arm of the yoke is provided with an upstanding centering pin 6 for cooperating with a depending centering pin 7 of the upper arm of the yoke, in forming a central pivot for a circular plate 8 to be flanged, the pin 7 being formed on the end of a manually-operable bolt 9 whereby the plate can be clamped firmly between the

centering pins to guard against slippage of the former.

Mounted upon the rails or trackway is a power element for imparting rotation to the plate 8. It is constructed as follows: 10 indicates a channel plate mounted directly on the rails 1, 11 a pair of angle plates secured to and rising from the opposite sides of plate 10, 12 a pair of angle plates mounted upon plates 11, and 13 a top or bridge plate connecting the opposite ends of the plates 12; the latter in their edges facing the adjustable yoke 4, being provided with notches or slots 14 for the accommodation or reception of the plate 8, as indicated in Figures 2 and 3.

A feed roller 15 underlying and engaging the plate 8, is journaled upon a stub shaft 16 mounted in a bearing block 17 rigidly stationed between plates 12 below the slots 14. An upper feed and clamping roller 18 engages plate 8 vertically above roller 15 for applying the power necessary to rotate said plate 8, and the roller is secured rigidly on a shaft 19 journaled in a bearing block 20 vertically adjustable between the plates 12, by means of a pair of bolts 21—22, suitably swivelled to said bearing block and connected together above the top or bridge plate 13 by a train of gearing 23, one of the adjusting bolts being provided with a hand wheel 24 for effecting operation of both bolts and the necessary vertical adjustment of the block 20, which block is provided at its opposite sides with guide ribs 25, engaging guide grooves 26 in the inner sides of the plates 12.

The shaft 16 is equipped at its outer end with a large gear wheel 27 meshing with a drive pinion 28 on a shaft 29 driven by any suitable power, not shown, for the purpose of operating the feed rollers and effecting the rotation of the plate 8.

The mechanism for turning the marginal portion of the plate to form a circular upstanding flange is as follows: A pair of parallel plates 30 extend in a direction approximately radial to the axis of a plate 8 of what may be considered the standard size. When a plate of smaller size is to be flanged, the yoke 4 is adjusted toward the feed rollers the requisite distance and in this case the plates 30

extend in a direction or plane which intersects the plate 8 at one side of its axis, as shown in Figure 2. If the plate 8 to be flanged is of oversize, the yoke 4 is adjusted away from the feed rollers, and in this event the plane of the direction of the plates or one of them, will intersect plate 8 at the opposite sides of its axis, it being understood that the plate 8, whatever its size, will always lie between and project beyond the feed rollers for rotation thereby and for the upturning of the marginal flange, the slots 14 and the spacing of the blocks 17 and 20 accommodating the flange.

10 The plates 30 are bolted to any suitable underlying support, and overlying the foot flange 31 of one of them, is an angle bracket 32 provided with an upstanding sleeve 33 in which fits a post 34 provided with a roller 35 engaging the underside of the plate 8 to form a marginal support therefor, a screw jack 36 providing an adjustable rest for the post, and a set screw 37 a means for securing the post against turning movement. A 15 bending roller 38 between the feed rollers 15 and roller 35, is journaled on a stub-shaft 39 secured in an internal web 40 of a toothed sector or rack-bar 41, fitting between plates 30 and provided with side tongues 42 engaging grooves 43 in said plates, the axis of the 20 sector being coincidental with the intersection point of the top of roller 38 with the face of the latter nearest the axis of the plate 8, as at such point the bending of the latter 25 plate is to occur. To effect the upward movement of the roller around the bending point as the axis thereof, a gear pinion 44 meshes with the sector and is mounted on a shaft 45 journalled in plates 30, and said shaft carries a gear wheel 46 meshing with a gear pinion 47 on shaft 48, operable by a crank 30 49 or other means.

An abutment or anvil upon which the flanges can be formed consists of a roller 50 arranged with its perimeter against the upper side of the plate 8 adjacent the axis around which the roller 38 turns. The roller is journaled on and supported by pin 52, depending from the crank arm 53 of a shaft 54 journalled in a bearing 55. The shaft 54 has a socket 56 in its upper end, receiving the lower end of a screw 57 mounted in the bearing and provided with a groove 58 engaged by a cap 59 threaded to shaft 54, the connection between the bolt and shaft being a swivel one to permit of vertical adjustment of the roller 50 without turning movement of the crank, it being practicable to readily turn the latter by a handle 53^a, to such position toward the yoke that the flanged plate can be withdrawn to a point beyond the feed rollers, it being apparent of course that the roller 18 must first be raised high enough for the flange of the plate to pass below it.

65 To provide for the free revolution of the

abutment roller, a ball bearing is employed, consisting of the roller, a cap member 55^a and a series of interposed balls 56^a, the cap member being rigidly mounted on the pin 52. The handle 53^a not only enables the 70 crank to be disposed for the convenient withdrawal of the plate when flanged as above explained, but also permits the operator to hold the crank shaft against accidental turning during the bending operation.

To secure a sharp bend it is essential that the roller makes contact with the plate. To accomplish this without applying unnecessary friction, the roller is tilted slightly as indicated in Figure 1, the tilting being accomplished preferably by tilting the bearing 55 carrying the crank shaft and its adjusting screw. To provide for tilting adjustment, the bearing has side flanges 60 secured by cap screws 61 to vertical blocks 62 secured to angle plates 63 carried by the plates 30, by cap screws 64, and mounted in the angle plates and blocks and bearing against the flanges of the bearing 55 above and below the horizontal center thereof are thrust screws 65. By advancing the upper and withdrawing the lower thrust screw, the bearing can be so adjusted as to slightly tilt the abutment roller 50 as shown, and leave it free to turn with the plate 8 as the bending operation occurs.

Assuming the parts are as disclosed by Figure 1, and that the plate 8 is being rotated by the feed rollers 15 and 18, the person in control manipulates the crank 49 and thereby rotates the sector upwardly to cause the flanging roller 38 to rise pivotally and bend the marginal portion of the plate 8 upwardly, this action continuing if desired until the flange is pressed flatly against the opposing face of the abutment roller. The rapidity of the operation is controlled by the manipulator of the crank 49, and requires at least one complete rotation of the plate 8. If the plate is of relatively heavy gage, it may describe several revolutions before the flange 105 is bent to the desired angle.

After the plate has been properly flanged, the abutment roller is shifted toward the yoke as explained, preliminary to the removal of the plate 8 and the feed roller 18 is of course raised to permit the plate to be shifted horizontally in the yoke after the screw 9 is manipulated to release it. If the plate 8 is of such diameter that it cannot be shifted side-wise sufficiently to withdraw it, and the yoke prevents sufficient movement longitudinally for the purpose, the screw can be operated to effect travel of the yoke on the trackway 120 away from the flanging mechanism to provide space for the withdrawal of the plate.

From the above description, it will be apparent that I have produced a circular plate flanging machine embodying the features of advantage pointed out as desirable, and while 130

I have described and claimed the preferred embodiment of the invention, it is to be understood that I reserve the right to make all changes falling within the spirit and scope of the appended claims.

5 5 I claim:—

1. In a plate flanging machine, an abutment roller engaging one face of the plate at the line where the bend is to be produced, a flanging roller engaging the opposite face of the plate outward of said line, a toothed sector carrying the flanging roller, means to rotate said sector to cause the flanging roller to bend the plate against the proximate face 10 of the abutment roller, driving means engaging the plate outward of its center to effect rotation of said plate and means for shifting the abutment roller inwardly of the plate to permit the latter to be shifted to cause its flange to approach the shifted abutment roller to disengage said plate from the driving means.

2. In a plate flanging machine, an abutment roller engaging one face of the plate at the line where the bend is to be produced, a flanging roller engaging the opposite face of the plate outward of said line, a toothed sector carrying the flanging roller, means to rotate said sector to cause the flanging roller 20 to bend the plate against the proximate face of the abutment roller, means for shifting the abutment roller inwardly of the plate to permit the latter to be shifted to cause its flange to approach the shifted abutment roller, a pair of feed rollers engaging opposite faces 25 of the plate, and means to withdraw from the face of the plate the feed roller at the side thereof toward which the flange is turned a distance exceeding the height of such flange.

3. In a plate flanging machine, an abutment roller engaging one face of the plate at the line where the bend is to be produced and having its axis tilted slightly from the vertical with respect to the surface of a plate 40 to be flanged and radially adjustable toward and from the periphery of said plate, a flanging roller engaging the opposite face of the plate outward of said line, means to effect pivotal operation of the flanging roller 45 on an axis coincidental with the bending line and toward the opposing side of the abutment roller, and means for holding the abutment roller tilted downward and outward toward the axial point of the flanging roller 50 movement and for advancing and retracting said roller toward and from the plate to be flanged.

4. In a plate flanging machine, an axial 55 support for a circular plate to be marginally flanged, feed rollers engaging opposite faces of the plate to turn the same, one of them adjustable toward and from the plate, an abutment roller engaging the same face of 60 the plate as the adjustable feed roller, a shaft

provided with a crank carrying the abutment roller, a flanging roller engaging the opposite side of the plate from the abutment roller and outward of the latter, and means for effecting pivotal operation of the flanging 70 roller on an axis adjacent the point of contact of the abutment roller with the plate.

5. In a plate flanging machine, an axial support for a circular plate to be marginally flanged, feed rollers engaging opposite faces 75 of the plate to turn the same, one of them adjustable toward and from the plate, an abutment roller engaging the same face of the plate as the adjustable feed roller, a shaft provided with a crank carrying the abutment 80 roller, a flanging roller engaging the opposite side of the plate from the abutment roller and outward of the latter, means for effecting pivotal operation of the flanging roller on an axis adjacent the point of contact of 85 the abutment roller with the plate, and means for effecting vertical adjustment of the abutment roller.

6. In a plate flanging machine, an axial support for a circular plate to be marginally flanged, feed rollers engaging opposite faces 90 of the plate to turn the same, one of them adjustable toward and from the plate, an abutment roller engaging the same face of the plate as the adjustable feed roller, a shaft 95 provided with a crank carrying the abutment roller, a flanging roller engaging the opposite side of the plate from the abutment roller and outward of the latter, means for effecting pivotal operation of the flanging roller on an axis adjacent the point of contact of the abutment roller with the plate, and a handle to operate the crank shaft when the flanging operation is complete or to hold it against 100 operation during the flanging operation. 105

7. A plate flanging machine, comprising a yoke for initially supporting a plate for rotation, feed rollers for rotating the plate, a roller for engaging the underside of the plate near its perimeter, an abutment roller overlying the plate and engaging the same at the point where the flange is to be turned, a bending roller underlying the plate, and means to pivotally operate the bending roller on an axis contiguous to the point where the abutment roller engages the plate. 110 115

8. A plate flanging machine, comprising a yoke for initially supporting a plate for rotation, feed rollers for rotating the plate, a roller for engaging the underside of the plate near its perimeter, an abutment roller overlying the plate and engaging the same at the point where the flange is to be turned, a bending roller underlying the plate, and means to pivotally operate the bending roller on an axis contiguous to the point where the abutment roller engages the plate, the yoke being adjustable toward and from the feed rollers and bending and abutment rollers. 120 125

9. In a plate flanging machine, a rotatable 130

abutment roller engaging one face of the plate at a line where the bend is to be produced and having its axis at substantially right angles to the surface of the plate said axis being offset as regards the axis of the 5 plate, a flanging roller engaging the opposite face of the plate outward of said line, means to rotate said flanging roller to bend the plate against the proximate face of the abutment roller, and means to advance and 10 retract said abutment roller toward and from the surface of the plate in a line coinciding with its axis of rotation.

10. In a plate flanging machine, a rotatable 15 abutment roller engaging one face of the plate at a line where the bend is to be produced and having its axis at substantially a right angle to the surface of the plate, a flanging roller engaging the opposite face of the plate outward of said line, means to rotate said flanging roller to bend the plate against the proximate face of the abutment roller, means to advance and retract said abutment roller in a line coinciding with its 20 axis of rotation, and means to move the abutment roller toward and from the perimeter of the plate.

11. In a circular plate flanging machine, a frame for holding a plate for rotation on its 30 center, a separate frame, means carried by said separate frame for imparting rotation to the plate, and means for flanging the periphery of the plate.

12. In a circular plate flanging machine, a frame for holding a plate for rotation on its 35 center, a separate frame, a pair of rollers carried by said separate frame and adapted to impart rotation to the plate, and means for flanging the periphery of the plate.

40 13. In a plate flanging machine, a support adapted to hold a plate for axial rotation, means adapted to engage the plate adjacent the periphery thereof for effecting rotation of said plate, an abutment roller adapted to engage the plate and movable toward and from the axis thereof, and a flanging roller in opposition to said abutment roller.

45 14. In a plate flanging machine, an abutment roller engaging one face of a rotating 50 plate to be flanged, a second roller in contact with the opposite face of said plate and in opposition to said abutment roller an arcuate guide, a sector mounted for movement on said arcuate guide, a flanging roller carried by said sector, and means for moving said sector on said guide.

55 15. In a plate flanging machine, an abutment roller engaging one face of a plate to be flanged, an arcuate guide, a sector mounted 60 for movement on said arcuate guide, a flanging roller carried by said sector, means for moving said sector on said guide, and means engaging the periphery of the plate to effect rotation thereof.

65 16. In a plate flanging machine, an abut-

ment roller for engaging one face of a rotating plate to be flanged and adjustable perpendicularly to the plane of said plate, an arcuate guide, a sector mounted for movement on said guide, a flanging roller carried by said sector, and means for moving said sector on said guide. 70

17. In a plate flanging machine, an abutment roller for engaging one face of a rotating plate to be flanged, a second roller in contact with the opposite face of said plate and in opposition to said abutment roller, an arcuate guide, a sector mounted for movement on said arcuate guide, a flanging roller carried by said sector, means for moving said sector on said guide, and means for moving the abutment roller perpendicularly toward and from the plane of the body of the plate to be flanged. 75

In witness whereof I hereunto affix my 80 signature.

VICTOR C. NORQUIST.
